UNITED STATES PATENT OFFICE.

CARL F. DOERE, OF YONKERS, NEW YORK.

ROTARY GLASS CUTTER.

1,424,625.

Specification of Letters Patent. Patented Aug. 1, 1922.

Application filed January 14, 1922. Serial No. 529,183.

To all whom it may concern:

Be it known that I, CARL F. DOERR, a citizen of the United States, and a resident of Yonkers, in the county of Westchester 5 and State of New York, have invented a new and Improved Rotary Glass Cutter, of which the following is a full, clear, and exact description.

This invention has relation to glaziers' 10 implements and has particular reference to an improvement in rotary glass cutters of the type set forth in my co-pending application Serial No. 463,693, filed April 22, 1921.

15 The present invention contemplates and specifically refers to an improved means for circumferentially adjusting the cutter head on the carrier sleeve therefor to simplify the construction of said means and the operation of bringing the various disc cutters into operative relation to the surface to be cut.

With the above recited and other objects in view, the invention resides in the novel 25 construction set forth in the following specification, particularly pointed out in the appended claims and illustrated in the accompanying drawings, it being understood that the right is reserved to embodiments other 30 than those actually illustrated herein to the full extent indicated by the general meaning of the terms in which the claims are expressed.

In the drawings—

35 Figure 1 is a plan view of the improved rotary glass cutter with the cutter head shown in section.

Fig. 2 is a side elevation of the same.

Fig. 3 is a transverse section taken approximately on the line 3—3 of Fig. 1.

Fig. 4 is a fragmentary longitudinal sectional view of the adjustable cutter head illustrating the manner in which the same is uncoupled from the carrier sleeve to permit of its adjustment.

Fig. 5 is a front face view of the cutter head removed from the carrier sleeve.

Referring to the drawings by characters, 10 designates the base of the improved rotary glass cutter which is provided on its under side with a lining 11 of felt or any other suitable material adapted to rest upon the surface of the glass 12 to be cut into a circular shape as will be hereinafter more 55 fully explained. The base 10 is provided with an upstanding post or pivot 13 having

a reduced threaded upper extremity 14. A bearing member 15 is mounted upon the upstanding post or pivot for horizontal turning movements and is retained against upward movement by a nut 16 threaded on the upper reduced extremity 14 of the bearing post or pivot. The pivot or post 13 with its reduced extremity 14 provides a shoulder 17 located a short distance above the top of the bearing member 15 to form an abutment for the nut 17, whereby to allow free turning movement of the bearing member 15 without binding by the nut.

The bearing member 15 is provided to one side of the pivot 13 with a transversely extending pivot pin 18 on which is mounted for vertical swinging movements the head 19 of a cutter carrier 20, preferably in the form of a bar attached to the head by the fitting of the inner end of the same into a socket 21, the same being retained therein by a set screw or pin 22. The cutter carrier 20 extends from the pivot 13 laterally in one direction and the head 19 is provided with an integral counter-balancing weight 23 extending in the opposite direction from the pivot 13. By the arrangement described the cutter carrier 20 is mounted for vertical swinging movements on the bearing member 15 which latter is mounted to turn on the vertical pivot 13. The nut 16 is preferably concave on the upper side to form a finger hold by means of which the operator may press the base 10 into firm contact with the 80 surface of the glass 12 during the cutting operation without interfering with the free rotation of the cutter carrier 20.

A supporting sleeve 25 having a square bore 26 corresponding to the size and shape 95 of the cutter carrier 20 is mounted thereon for longitudinal sliding movement and is adapted to be adjustably secured in place by a set screw 27 or any other suitable fastening device. The sleeve is provided at its inner end with a circumferential flange 28 and an enlarged peripheral bearing portion 29 which is threaded as at 30 adjacent its juncture with the major portion of the sleeve proper. The cutter head 31 is in the nature 100 of an annulus which snugly fits over the enlarged peripheral portion 29 of the carrier sleeve 25 and is provided with a peripheral or circumferential groove 32 in which the disc cutters 33 are mounted and 105 circumferentially spaced. The flange 28 is provided with a laterally projecting locking

key 34 and the cutter head with a plurality of circumferentially spaced key-ways 35 adapted to selectively receive the locking key 34 to position and arrange one of the disc cutters in cutting relation to the glass. A retaining nut 36 is threadedly engaged with the threads 30 to retain the cutter head 31 into engagement with the flange 28 and the locking key 34 in locking engagement with one of the key-ways 35. When it is desired to bring another of the cutting discs 33 into operative position, the locking nut 36 is unscrewed as illustrated in Fig. 4 to permit axial shifting of the cutter head and relative separation of the same from the flange 28 whereby the key-way 35 will be disengaged from the locking key 34. This uncouples the cutter head 31 from the carrier sleeve to permit free circumferential movement of the same thereon whereby any of said key-ways may be brought into registry with the locking key 34. When the desired adjustment has been obtained the cutter head 31 is advanced toward the flange 28 and the nut 36 is again threaded thereagainst to retain the cutter head in its adjusted position. The set screw 27 which affords means for locking the sleeve 25 in its longitudinal adjusted positions on the carrier bar 20, also functions as a stop for engagement with the nut 36 to prevent the entire unthreading of the same from the threads 30 thereby eliminating the trouble incident to re-engaging the threads and also preventing possible stripping of the same. Under this arrangement the disc cutters which are here illustrated as six in number are designed to be used one at a time and when dull the cutter head can be readily adjusted on the sleeve to bring another of the cutters into cutting position. When all the cutters have become dull they can be readily removed from the cutter head 31 and replaced by new ones.

I claim:

45 1. In a cutting implement having a plurality of cutters adapted to be selectively brought into cutting relation, embodying a cutter bar, a carrier sleeve longitudinally adjustable thereon, a stationary abutment at one extremity thereof, an axially movable abutment thereon, a cutter head mounted for axial and rotary movement on the sleeve between said abutments having circumferentially spaced cutters projecting from the periphery thereof and interengageable means on the confronting faces of the stationary abutment and the cutter head adapted to lock said elements against relative axial and rotary movement upon clamping engagement of said cutter head between the stationary and movable abutments.

60 2. In a rotary glass cutter, a cutter bar, a sleeve adjustably fastened to said cutter bar, a peripheral flange at one extremity of the sleeve, a locking key projecting inwardly

therefrom, a cutter head provided with circumferentially spaced cutters projecting from the periphery of the cutter head, said cutter head having an annular series of axially disposed key-ways in the face confronting the flange, the said cutter head being mounted to turn and slide on said sleeve for effecting selective engagement of the locking key with the key-ways, and means for securing said cutter head against axial sliding movement to maintain the locking key within one of the key-ways.

3. In a rotary glass cutter, a cutter bar, a sleeve mounted for longitudinal adjustments on said cutter bar, a cutter head provided with circumferentially spaced cutters projecting from the periphery thereof, the latter being mounted for rotary and axial movements on the sleeve and means for securing said cutter head in its adjusted position on the sleeve to selectively dispose one of the cutters in cutting relation, comprising a peripheral abutment at one end of the sleeve, an inwardly projecting locking key on said abutment and a portion of said cutter head having an annular series of axially disposed key-ways adapted to selectively receive the locking key, and means for locking the cutter head in engagement with the abutment.

4. In a rotary glass cutter, a cutter bar, a sleeve mounted for longitudinal adjustments on said cutter bar, a set screw threaded transversely through said sleeve for securing the same in its longitudinally adjusted positions on the cutter bar, a cutter head provided with circumferentially spaced cutters projecting from the periphery thereof, the latter being mounted for rotary and axial movements on the sleeve, and means for securing said cutter head in its adjusted position on the sleeve to selectively dispose one of the cutters in cutting relation, comprising a peripheral abutment at one end of the sleeve, an inwardly projecting locking key on said abutment and a portion of said cutter head having an annular series of axially disposed key-ways adapted to selectively receive the locking key, and a nut threaded on the sleeve for axial movement to afford means for advancing the cutter head toward and retaining the same in engagement with the abutment, the said set screw coacting with the nut to prevent complete unthreading of the same from the sleeve.

5. The combination with a rotary glass cutter including a base adapted to rest on the glass and having an upstanding pivot, a bearing member mounted for complete rotation on said pivot, a counterbalanced cutter bar pivoted to said bearing member, a cutting element adjustably mounted on the cutter bar comprising a sleeve mounted for longitudinal adjustments on said cutter bar, a cutter head provided with circumfer-

tially spaced cutters projecting from the periphery thereof and mounted for rotary and axial movements on the sleeve to selectively bring the cutters in cutting position, of
5 means for securing said cutter head in adjusted positions on the sleeve embodying a peripheral flange at one end of the sleeve, an inwardly projecting locking key on said

flange, a portion of said cutter head having an annular series of axially disposed keyways for selectively receiving the locking key, and axial movable means for advancing the cutter head toward and retaining the same in abutting engagement with the flange.

CARL F. DOERR.
